JULIAN W. MAXSON, OF WESTERLY, RHODE ISLAND.

COUNTING AND MARKING MACHINE.

Application filed May 24, 1922. Serial No. 563,274.

The present invention relates to counting and marking machines, and its chief object is to provide an improved machine for counting the number of sheets of paper or the like that are delivered by a sheet-delivery machine into a lay-boy or other magazine, and for marking or separating the sheets so delivered into bundles or reams, each containing a predetermined number of the sheets.

10 The invention will be fully explained in connection with the accompanying drawings, in which Fig. 1 is a diagrammatic view, partly in side elevation and partly in longitudinal section, of a paper-sheet-cutting machine of well known construction, with the present invention attached thereto; Fig. 2 is a rear view of a stack of sheets as delivered into the lay-boy shown in Fig. 1, counted and marked in accordance with the present invention; Fig. 3 is a side elevation of a portion of the machine shown in Fig. 1; Fig. 4 is a plan of the forward portion of the machine shown in Fig. 1; Fig. 5 is a plan of one of the intermittently operating tag-feeding devices and associated parts, shown enlarged with respect to Fig. 1; Fig. 6 is a side elevation of the structure shown in Fig. 5; Fig. 7 is a front elevation of a portion of the same; Fig. 8 is a section, taken upon the line 8—8 of Fig. 5, looking in the direction of the arrows; Fig. 9 is a further enlarged side elevation of a portion of the operating mechanism of the tag-feeding devices, the parts being shown in the relative positions occupied by them when the tag-feeding devices are ineffective; Fig. 10 is a similar view, with the parts in relative positions such as to render the tag-feeding devices effective to feed the tag; Figs. 9^a and 10^a are similar views, showing further steps in the operation; Fig. 11 is a section, upon the same scale, of a portion of the said operating mechanism, the section being taken generally upon the line 11—11 of Fig. 9, looking in the direction of the arrows; Fig. 12 is a view similar to Fig. 6 of a modification; Fig. 13 is a front elevation of the counter-containing casing, shown enlarged as compared to Fig. 3; Fig. 14 is a vertical section of the same, taken substantially upon the line 14—14 of Fig. 3, looking in the direction of the arrows; Fig. 15 is a section taken upon the line 15—15 of Fig. 14, looking in the direction of the arrows, portions being omitted for clearness; Fig. 16 is a

view similar to Fig. 15, showing the parts in relatively different positions; Fig. 17 is a side elevation of the counter casing shown in Fig. 13, showing also associated parts; Fig. 18 is a section taken substantially upon the line 18—18 of Fig. 14, looking in the direction of the arrows; Fig. 19 is a view of a detail; and Fig. 20 is a section taken upon the line 20—20 of Fig. 4, looking in the direction of the arrows.

65 The machine of the present invention is, for illustrative purposes, shown applied to a paper-sheet-cutting-and-feeding machine of well known type, such as is commonly employed in paper mills to sever the rolls 2 of paper, Fig. 1, that are produced in the paper-making machines, into individual sheets, and to feed and stack the severed sheets into lay-boys 4. Any desired, convenient number of rolls 2 of paper may be operated upon simultaneously in the same machine. Three such rolls are illustrated diagrammatically in Fig. 1. The webs 3 of paper from the rolls 2 are led together to feed rolls 6, by which the paper is advanced to disk cutters 8, which sever the paper into longitudinal strips of the desired width. The severed strips are then advanced by feed rolls 10 and 12 to rotary cutters 14 and 16 by which the strips are severed into sheets of the desired 75 length. Tapes 18 and 20 then feed the sheets into the lay-boys 4, which are automatically lowered from time to time to maintain approximately uniform the level 80 of the sheets that are stacked therein.

85 The sheets so stacked in the lay-boys 4 are separated into bundles, each containing a predetermined number of the sheets. It is customary to separate them into reams of 480 or 500 sheets. According to present practice, this separation is effected during the sheet-stacking process in the lay-boys by girls or other operatives who stand in front of the lay-boys, at 22, Fig. 4, and mentally count the sheets, one by one, as they are delivered. The girls place a paper tag between two adjacent sheets at the completion 90 of each count. These tags are inserted from the front of the stack, at 22. The completed stack is thus supposed to be separated by 95 these tags into reams or bundles of any desired number of sheets. The accuracy of the count, however, depends upon an inherently inaccurate or undependable mental counting process. Automatic counting and marking

devices of various kinds have accordingly been proposed at various times in the past, but for one reason or another,—whether too complicated, or cumbersome, or unreliable in practice (however operative in theory), or unsuited to the needs of the particular machine,—they have not proved to be satisfactory, so that the girls are still universally employed, and it is still impossible to tell, in 10 advance, how many sheets a mentally-counted ream really contains.

According to the present invention, the sheets are counted automatically, as they are delivered into the lay-boy 4, by an accurate 15 machine that is not dependent upon a failing human counting memory; and thin, paper tags 24, Figs. 1 and 2, are automatically inserted between adjacent, predetermined sheets at the completion of each count; so 20 that the reams or bundles thus counted and marked contain just the desired number of sheets, and neither more nor less. Not only are accuracy and efficiency thus attained for the first time, but the cost is considerably reduced, since the girls are no 25 longer needed, and may be employed to better advantage elsewhere.

Feed rolls 26 and 27, Fig. 6, automatically advance intermittently, through a guide 28, 30 and between a movable knife 30 and a stationary knife 32, Fig. 7, a paper strip 34 that is unwound from a reel 36. The end 38 of the paper strip, is thus intermittently advanced, at the proper time, and becomes inserted between adjacent sheets 104 and 106, 35 Fig. 1, of the stack, and, after it is severed by the knives 30 and 32, constitutes a tag 24. The feed roll 27 is idly mounted upon an end of a bell-crank lever 40, the other end of 40 which is weighted at 42 to cause the feed roll 27 to maintain the paper strip tightly in engagement with the feed roll 26. To advance the strip 34, therefore, it is necessary to rotate intermittently the feed roll 26 only. The 45 feed roll 26 is rotated by rotating a shaft 44 upon which it is secured. This shaft 44 is intermittently rotated by a continuously rotating pawl 46, Figs. 9, 10, 9^a, 10^a and 11, when the latter engages the walls of a recess 48 provided upon a normally stationary 50 collar member 50 that is fixed to the shaft 44. The recess 48 is thus, in effect, provided upon the shaft 44. The pawl 46 is pivotally mounted at 52 upon a collar 54 that is keyed 55 at 55 to a sprocket wheel 56. The sprocket wheel 56, with the collar 54 that is keyed thereto, is loosely mounted upon the shaft 44. The sprocket wheel 56 is driven by a sprocket chain 58, Figs. 3, 4 and 17, from a 60 sprocket wheel 60 that is mounted upon a shaft 62 (see also Fig. 14). An idler sprocket wheel 59 is interposed, as a convenient medium of properly determining the 65 direction of rotation of the sprocket wheel 56. The shaft 62 is driven by a sprocket

wheel 64 through the medium of a sprocket chain 66, Figs. 3, 4 and 17, that is mounted over a sprocket wheel 68 provided upon the shaft of the rotary cutter 16. The rotation of the shaft 62 is therefore a measure of the 70 number of sheets that are cut by the knife 16 and delivered into the lay-boy 4. The collar 54, that carries the pawl 46, is thus continuously rotated loosely in a circular path about the shaft 44, from the shaft of the cutter 16, so long as the pawl 46 does not engage the walls of the recess 48. When the pawl 46 does engage the walls of the recess 48, however, it will actuate the recess-carrying collar 50; and the shaft 44, to which the 80 recess-carrying collar 50 is secured, will obviously rotate also, causing the feed rolls 26 and 27 to feed the end 38 of the strip 34 between two adjacent sheets 104 and 106 of the stack, as is illustrated in Fig. 1. The feeding of the strip 34 is therefore controlled by the continuously rotating pawl 46. Rotation of the shaft 44 in the wrong direction is prevented by one or more pawls 69, Figs. 4 and 20, operating, with graduated effect, 85 upon one or more ratchet wheels 71.

The pawl 46 is normally prevented from entering the recess 48 by a gate 70, Figs. 9, 10, 9^a, 10^a and 11, that is provided upon a collar 72 that is loosely mounted upon the 95 reduced end 74 of the shaft 44. In the position normally occupied by the collar 72 upon the shaft 44, the gate 70 overlies or covers the forward wall 49 of the recess 48, as shown in Fig. 9, in the path of the pawl 100 46. So long as the gate 70 overlies this forward wall 49 of the recess 48, the continuously rotating pawl 46 can not engage the wall 49, but rides idly over the gate. Upon the gate becoming displaced from the position 105 of Fig. 9 to that of Fig. 10, the pawl 46, during its next journey around the shaft 44, will be pressed into the recess 48 by a spring 76. The pawl 46, continuing its rotation, will now carry the recess-containing collar 50 110 with it, and the latter, being secured to the shaft 44, will cause the feed roll 26 to advance the end 38 of the strip 34, as above described. Upon reaching the wall 78, Fig. 10, of the gate 70, the pawl 46 will ride out 115 of the recess 48, as shown in Fig. 9^a, whereupon the shaft 44 will cease rotating, and the strip 34 will be no longer advanced. The forward wall 49 of the recess 48 will thus be left behind the gate 70, in the dotted-line 120 position of Fig. 9^a. The pawl 46 will then again continuously rotate idly, as before. It should be noted that when the pawl 46 leaves the forward wall 49 of the recess 48 125 behind the gate 70, as just described, the shaft 44 has not quite completed a revolution, for the recess 48 occupied originally the position shown in full line in Fig. 10, whereas it now occupies the position shown 130 in Fig. 9^a. The revolution of the shaft 44 is

completed later, as will shortly be described, to effect the actuation of the movable knife 30.

It will now be necessary to explain how the gate 70 is actuated from the position of Fig. 9 to that of Fig. 10 to uncover the recess 48, and thus permit the pawl 46 to actuate the feed roll 26 by engaging the wall 49 of the recess 48. The gate 70 is provided with a pin 80 that projects into an elongated opening 82, Figs. 11 and 17, provided at one end of a lever 84. The lever 84 is intermediately pivoted at 86, and its other end 88 (see also Fig. 14) rides along a cam track 90 of a cam disk 89 that is rigidly secured to a counting disk 92 so as to rotate therewith. The cam track 90 is provided with a recess 94 having a sharp, abrupt shoulder 96, a gradually inclined shoulder 98 and an intermediately disposed wall 100. The counting disk 92 and the cam disk 89 are rotated, step by step, as will hereinafter be described, in the direction of the arrow, Fig. 17. When the sharp, abrupt shoulder 96 reaches the end 88 of the lever 84, a spring 102 will move the lever 84 to cause the end 88 of the lever to engage the wall 100 of the recess 94. The other end of the lever 84 will thus be moved downward, as viewed in Fig. 17, causing the pin 80 to be moved downward also. The collar 72 will therefore be rocked from the position of Fig. 9 to that of Fig. 10, causing the gate 70 to uncover the recess 48. The pawl 46 will then be enabled to cause actuation of the feed roll 26, as above described.

The downward movement of the lever 84 is timed to take place at the end of a cycle of operation of the counter; say, after a ream has been delivered and counted. It is sometimes convenient to notify the operator that another ream has been delivered in the lay-boy, as he may be waiting to remove it. This notification the machine does automatically, leaving the operator free to attend to other duties in the meantime. When the lever 84 moves down, it carries with it a striker 101 that strikes a bell 103. Not only does the machine count and mark, therefore, but it also signals at the end of the completion of each count, the strip-inserting means and the signalling means being both controlled by the lever 84. The signalling may also be used to notify an operator to insert a tag manually, in case the marker is not working properly.

It has been pointed out above that the pawl 46 will leave the recess 48 at a time when the latter is in the position of Fig. 9^a, and before the shaft 44 has made a complete revolution. This nearly complete revolution of the shaft 44 is effected in about half the time required to make one delivery into the lay-boy. During this nearly complete revolution of the shaft 44, the end 38 of the strip 34 has been rapidly fed from the rear of the stack, in an

upwardly inclined direction, as shown in Figs. 1 and 6, over the last sheet 104 of the ream just completed, and under the line of feed of the next following sheet, which constitutes the first sheet 106 of the next ream. It is therefore preferred to feed the strip as illustrated and described in a copending application, Serial No. 664,775, filed September 25, 1923. If the end 38 of the strip were fed horizontally forward, being constituted of thin paper, it might strike the rear of the stack of sheets, and not enter between adjacent sheets at all, thus failing to mark the separating line between the reams. When the end 38 has thus been laid flat by the sheet 106 upon the sheet 104, it is still too early to sever it from the strip 34, as the severing process might pull it out of place. It is preferable to wait until a number of sheets have been fed forward over the sheet 106; their combined weight then serving to hold the end 38 of the strip 34 in place while it is severed. The number of sheets that shall so be fed forward for this purpose depends upon the length of the wall 100 of the recess 94. As the counting disk 92 continues to rotate, as it counts the additional sheets so fed forward, the end 88 of the lever 84 will ultimately leave the wall 100 and ride up on the inclined shoulder 98 of the recess 94. The other end of the lever 84 will then be returned upward to its normal position, shown in Fig. 17, carrying the pin 80 upward with it. This will have the effect of returning the gate 70 from the position of Figs. 10 and 9^a to that of Figs. 9 and 10^a, uncovering the forward wall 49 of the recess 48, which at this time occupies the dotted-line position of Fig. 9^a, as explained above. During the next cycle of rotation of the pawl 46 about the shaft 44, therefore, it will engage the forward wall 49 of the recess 48, and thus actuate the recess-carrying disk 50 from the position of Figs. 9^a and 10^a to the position of Fig. 10. Upon the recess 48 being thus returned to the position of Fig. 9, the gate 70, occupying now the position shown in Figs. 9 and 9^a, will again cause the pawl 46 to leave the recess 48, and the pawl 46 will again continue to rotate idly, as before. This completes the revolution of the collar 50 and, therefore, of the shaft 44 to which it is secured. Upon the completion of this revolution, the knife 30 will actuate to sever the end 38 from the strip 34, the severed end constituting one of the tags 24. The lever 84 is thus adapted to occupy two positions successively, in one of which it controls the feed roll 26 to insert the end 38 of the strip 34 between adjacent sheets of the stack, and in the other of which it causes the knife 30 to sever the end 38 of the strip, these two positions being controlled by the cam disk 89. The mechanism for operating the knife 30 will now be described.

One end of the knife 30 is shown in Fig. 7 as pivoted at 108. The knife is adapted to be moved in a vertical plane about the pivotal point 108, to cooperate with the stationary 5 knife 32, by a bell-crank lever 110 to one end of which the other end of the knife is pivoted at 112. The lever 110 is intermediately pivoted at 114, its other end 116 engaging a rotary cam 118. When the recess 48 is moved by 10 the pawl 46 from the position of Figs. 9^a and 10^a to the position of Fig. 9, the end 116 of the lever 110 is pulled by a spring 120 into a recess 123 provided in the rotary cam 118. The lever 110 is thereby pivotally actuated 15 about the pivotal point 114 to move the knife 30 upward, as seen in Fig. 7, causing the end 38 to become severed from the strip 34. The roll cam 118 is loosely mounted upon a stationary shaft 122, and is connected to a 20 gear 124, shown more particularly in Fig. 5, so as to rotate therewith. The gear 124 is also loosely mounted about the shaft 122, and meshes with a gear 126 that is secured to the shaft 44 so as to rotate with the feed 25 roll 26. The knife is thus operated in timed relation to the operation of the feed roll 26, the feed roll first operating through nearly a complete revolution to feed the strip 34, and then, later, through the remainder 30 of its revolution to cause the end 116 of the lever 110 to enter the recess 123, thereby causing the knife to sever the end 38 from the strip 34. The knife is returned to normal 35 position before the shaft 44 comes to rest. The cam roll 118 is adjustable to adjust the time of operation of the knife 30. A partition 134 separates the rolls 26 and 118 from the gears 124 and 126 to prevent the paper strip 34 binding between the gears 40 and clogging the machine.

There is a tendency for the strip 34 to sag or buckle in the guide 28. This may cause the strip to crumple until, finally, the strip 45 may get stuck in the guide 28, so that the end 38 can not be advanced at all. To prevent such effects, the real feeding of the strip should be done at a point closer to the stack 50 of sheets than is shown in Fig. 6 and, if possible, at a point just rearward of the knives 55 30 and 32. In the modification of Fig. 12, therefore, the feeding action is performed by feed rolls 260 and 270 that are situated at the forward end of the guide 28. The feed roll 260 is directly driven from the gear 126 60 by a train of gearing 128. The feed roll 270, like the feed roll 27 of Fig. 6, is an idler roll, being idly mounted pivotally upon the end of an arm 130 that is pivoted at 132. The feed roll 270 acts by gravity to maintain 65 the paper strip 34 tightly against the feed roll 260.

It has now been explained how the end 38 of the strip is automatically advanced into position between the adjacent sheets 104 and 106 of adjacent reams, and how it is then

severed from the strip 34, the tag 24 being thus left in place to mark the boundary between the two reams. It has been explained that the successive operations of the feeding and severing mechanisms for the strip 34 70 are controlled by the end 88 of the lever 84, through the recess 94 in the cam disk 89 that is secured to rotate with the counting disk 92. It remains, therefore, to describe the operation of the counter.

75

As has been explained above, the shaft 62 of the counter is driven by the sprocket chain 66 from the shaft of the rotary knife 16. The rotation of the shaft 62 is therefore timed to the rotation of the rotary 80 knife 16 and is therefore a measure of the number of sheets that are cut by the knife 16 and stacked in the lay-boy, as has already been mentioned. The teeth of a pinion 150, Figs. 14 and 18, that may be 85 adjustably connected to rotate with the shaft 62, mesh with gear teeth 152 that are provided upon the periphery of the counting disk 92. The angular movement of the counting disk 92 is thus timed with relation to the operation of the knife 16, and may be measured upon a stationary scale 154, Fig. 17, extending through an arc of approximately ninety degrees. The counting disk 92 is visible through an opening 156 90 in the upper portion 202 of the counter-containing framework, so that the degree of angular movement of the counting disk relative to the casing may be read off upon the scale by noting the position, relative to 95 the scale, of one of five indicators 158, respectively marked 0, 1, 2, 3 and 4, upon the front face of the counting disk 92. In the relative positions shown in Fig. 17, for example, the counter indicates that a little 100 over 270 sheets have been delivered into each lay-boy. The parts are so proportioned that each revolution of the shaft of the cutter 16 may effect an angular movement of the counting disk 92 corresponding 105 to any desired integral number of sheets from zero to 26, depending upon the adjustable connection of the pinion 150 to the shaft 62.

To this end, the pinion 150 is not rigidly 115 secured to the continuously rotated shaft 62, but is loosely mounted thereon. A ratchet wheel 160 is fast to the pinion 150 so as to rotate therewith. The operation of the counting disk 92 is thus controlled by 120 the teeth of the ratchet wheel 160. The ratchet wheel 160 is intermittently actuated through a predetermined angular extent by a pawl 162. The pawl 162 is pivotally connected at 164 to the free end of an arm 166 125 that is fast to the shaft 62 so as to rotate therewith. As the shaft 62 rotates continuously, therefore, the pawl 162 is continuously rotated in a circular path about the shaft 62 as a center. In some positions of 130

its circumferential movement, the pawl 162 is actuated by a spring 168 into engagement with one of the ratchet teeth of the ratchet wheel 160. The ratchet wheel 160 is then caused to rotate with the pawl 162 until a tail 163, Fig. 14, of the pawl is engaged by an inclined face 170 of a cam track 172. The cam track 172 is constituted of the circular surfaces of segmental disks 180, 182 and 184, described below. The pawl 162 is thereupon disengaged from the teeth of the ratchet wheel and rides idly over the cam track 172 until, during the next cycle of its rotation, the pawl is permitted by an abrupt shoulder 174 to be actuated by the spring 168 into engagement with another tooth of the ratchet wheel 160. In this manner, the ratchet wheel is intermittently actuated through an arc corresponding to the number of ratchet teeth between the abrupt shoulder 174 and the inclined face 170, and the counting disk 92 is correspondingly controlled in accordance with the degree of actuation of the ratchet wheel. The distance between the abrupt shoulder 174 and the inclined face 170 may be so adjusted as to have between them any desired convenient number of teeth of the ratchet wheel 160. In Fig. 15, this desired number is shown to be three. During each revolution of the pawl 162, therefore, the ratchet wheel 160 will be actuated by the pawl 162 through an arc corresponding to three teeth and will cause the counting disk 92, through the pinion 150, to be moved through an arc corresponding to three sheets, as indicated upon the scale 154. This will keep the count accurate, as the sheets are fed by threes, as illustrated, into the lay-boys from the three rolls 2.

The step-by-step movement of the counting disk 92 is thus controlled by the action of the pawl 162, which operates in one direction only, in accordance with the operation of the cutter 16. Upon each revolution of the pawl 162, the counting ratchet wheel 160 is moved, always in the same direction, through a predetermined angle corresponding to the number of teeth of the ratchet wheel 160 that are exposed between the abrupt shoulder 174 and the inclined shoulder 170. The counting disk 92 is correspondingly moved. In practice, the ratchet wheel 160 has a tendency to overrun after the pawl 162 has been disengaged from its teeth by the inclined shoulder 170. This overrunning would be communicated, through the pinion 150, to the counting disk 92, which would destroy the accuracy of the count. A friction brake 175 is therefore employed to prevent overrunning of the ratchet wheel 160. As shown in Figs. 13 and 14, the preferred brake comprises two shoes mounted to clamp frictionally between them a hub 177 that is integral with the counting disk 92. The shoes are yieldingly held together against the hub 177 by coil springs 179 that are mounted over rods 181 between one of the shoes of the brake and nuts 183. The other shoe rests against a portion 185 of the frame work, which prevents rotation of the brake along with the counting disk 92. The frictional effect of the springs 179 is sufficient to prevent overrunning of the ratchet wheel 160 and, therefore, of the counting disk 92. The various parts of the counter operate always in the same direction of operation throughout, and they thus operate to just the proper degree.

The degree of angular movement of the ratchet wheel 160 that is effected upon each revolution of the pawl 162 may be adjusted during the operation of the machine by a handle 176, Figs. 13, 14 and 17. This handle is rigidly secured at 178 to the segmental disk 180, the arc of the segment of which is approximately 120 degrees. Together with the two other, similar, segmental discs 182 and 184, in side-by-side relation, the disc 180 is mounted, upon the shaft 62, as shown in Figs. 14, 15 and 16, the discs 180 and 182 loosely, and the disc 184 fixedly. The intermediately positioned disc 182 is provided upon one face with a pin 186 that projects into an arcuate opening 188 of the disc 180. The disc 182 is similarly provided upon its opposite face with a similar pin 190 projecting into a similar arcuate opening 192 of the disc 184. The discs may therefore be angularly moved relatively to each other about the shaft 62 by means of the handle 176, the pins 186 and 190 riding freely in the respective openings 188 and 192. By moving the handle in the direction of the arrow, Fig. 15, therefore, the distance between the abrupt shoulder 174 and the inclined face 170 may be increased. By moving it in the opposite direction, the distance may be decreased. The predetermined number of counting-disk-controlling teeth of the ratchet wheel 160 that are exposed between the abrupt shoulder 174 and the inclined face 170 may therefore be varied, at will, from zero to the number found in an arc of approximately 240 degrees. This corresponds to an intermittent feed of from zero to 26 sheets, corresponding to each revolution of the pawl 162. The segmental discs 180, 182 and 184 may be maintained in adjusted position by a spring-pressed plunger 194, Fig. 14, engaging in any one of a number of openings 196, corresponding to the adjustable positions of the handle 176. In practice, the handle 176 will be adjusted to the number corresponding to the variable number of rolls of paper 2, or of the superposed webs 3, that at any one time supply material to the machine. Three such rolls are shown in Fig. 1, and the handle 176 will therefore be set to the numeral 3 in Fig. 17, so that three

sheets may be registered by the counter disc 92 upon each rotation of the shaft of the cutter 16. Half reams may obviously be marked by setting the handle 176 to cause the counter to count double, and so for other multiples also.

The counter may be adjusted during the operation of the machine to count in any desired multiples. If it is desired to count by fives instead of by threes, for example, all that the operator has to do is to move the handle 176 from the position numbered 3 in Fig. 17, to the position numbered 5, and to permit the spring-pressed plunger 194 to become seated in the corresponding opening 196. This capability of ready adjustment during the operation of the machine is of great value to correct errors in the count. If some of the sheets delivered to the lay-boy should prove to be defective, or if it should be desirable to remove a few sheets from the lay-boy for some other reason, all that is necessary is to adjust the handle 176 to some lower number. Let it be assumed, for example, that the handle has been adjusted to zero on the scale. The machine will then continue to feed by threes, but the counter will no longer count. When enough sheets have been fed into the lay-boy to correct the count, the handle 176 may be returned to its proper place, and the counter will continue to count as before, and the error in the count due to the discarded sheets will have been corrected or compensated for. The handle 176 may be kept at zero when the machine is first started until the machine is properly operating, when it may be set correctly. The adjustment is made during the operation of the machine, without stopping the machine.

It will be clear from the above description that any desired number of feed rolls 26 and associated mechanisms may all be mounted upon and controlled by the same shaft 44. Three lay-boys 4 are shown in Fig. 4, each provided with a separate marking attachment adapted to supply tags 24. As the feed rolls 26 of the three markers are mounted upon the same shaft 44, a single counter suffices for all three lay-boys. As many lay-boys as are attached to the machine may each be provided with a marker.

The markers, as is explained above, are controlled by the counter. If it is desired to count and mark reams of 500 sheets, a counting disks 92 having a suitable number of gear teeth 152 will be employed. If it is desired to count reams of 480 sheets, a counting disk 92 having a different number of gear teeth 152 will be employed; and similarly with any other number of sheets counted. In each case, the markers will be operated at the end of the desired count, as determined by the number of teeth upon the counting disk 92 that is employed. Obvi-

ously, too, it is not essential that the markers be operated once to every revolution of the counting disk 92, for cam disks 89 having a plurality of recesses 94 may be employed, the location of the recess 94, in each case, controlling the operation of the markers. The counting disk 92 may be removed by unloosening bolts 200, Fig. 13, and removing the portion 202 of the framework within which the counting disk 92 and connected parts, including the cam disk 89 and the brake 175, are mounted. A similar portion of the framework, in which another counting disk 92 is journaled, may then be placed in position in substitution for the removed framework.

Ordinarily, but two counting disks are employed,—one to count reams of 500 sheets, and the other to count reams of 480 sheets. It is possible to design the machine so as to count either one or the other ream without removing and replacing counting disks 92. The duplex type of paper-cutting-and-feeding machine shown diagrammatically in Fig. 1 is particularly adapted to such design, since it is possible to employ it in connection with two counters, one controlled by the cutter 16, as above described, and the other controlled by the cutter 14. The two counters may be mounted at opposite sides of the machine, as is illustrated in Fig. 4. The operation of the counter that is controlled by the cutter 16 has already been described. The other counter may be driven from the cutter 14 by a sprocket chain 208. This sprocket chain drives a shaft 210 that extends across the machine and that is provided at the other side of the machine with a sprocket wheel 212. The sprocket wheel 212, at one side of the machine, is thus driven directly from the knife 14 by the sprocket chain 208 that is provided at the other side of the machine. A driving connection of this character is preferred because gearing (not shown) that is usually employed in such machines would interfere with driving the sprocket wheel 212 by a sprocket chain provided at the same side of the machine. The sprocket wheel 212 controls the one counter in much the same way that the sprocket wheel 68 controls the other counter, the sprocket chains 214 and 216 corresponding to the sprocket chains 66 and 58, respectively, and the lever 218 corresponding to the lever 84. As has been explained above, the lever 84 controls, through the pawl 46, the operation of the shaft 44, this shaft, in turn, controlling the feed wheel 26 to which it is keyed. The lever 218, on the other hand, controls, through a similar pawl, the operation of the shaft 122.

It has been explained above that the feed wheel 26 and the gear 126 are keyed to the shaft 44, and that the cam roll 118 and the gear 124 are loose on the shaft 122. To op-

erate the markers from the shaft 122, through the lever 218, the key 220, Fig. 6, is removed, so as to render the feed wheel 26 and the gear 126 loose upon the shaft 44, and the roll 118 and the gear 124 are keyed at 222 to the shaft 122, instead. Rotation of the shaft 122 will thus carry the cam wheel 118 and the gear 124 with it; and the rotation of the gear 124 will be communicated, through the gear 126, to the feed wheel 26, the feed wheel 26 and the gear 126 now rotating idly on their shaft 44. The feed wheel 26 is thus operated to feed the strip 34 in the same manner as before described, except that it is now operated from the shaft 122 instead of from the shaft 44; and the knife-controlling-cam wheel 118 still operates to control the knife, being now driven directly from the shaft 122 instead of indirectly, from the shaft 44.

The feed roll 26 and the cam roll 118 are thus so connected, through the gears 126 and 124 respectively, that the rotation of either roll will effect the rotation of the other. The rolls are loosely mounted upon their respective shafts, but one or the other, depending upon which counter is to be employed, is keyed to its shaft to effect the feeding of the strip 34.

The lever 218 is shown in detail in Fig. 19. The pivotal point 224 corresponds to the pivotal point 86, Fig. 17, of the lever 84. The end 226 of the lever 218 corresponds to the end 88 of the lever 84. The other end is provided with an elongated opening 228 that corresponds to the opening 82, and is adapted to receive a pin that corresponds to the pin 80 for controlling the shaft 122. The opening 228 is somewhat differently inclined from the opening 82 because of the different relative positions of the shafts 44 and 122. To cooperate with the lever 218, the shaft 122 extends beyond the machine at the right, as viewed in Fig. 4, just as the shaft 44 extends out at the left, Fig. 11, to cooperate with the lever 84.

By this arrangement, therefore, the same markers may be controlled by one or the other of two counters, at the will of the operator, so that reams of different numbers of sheets may be counted without disassembling the counters.

The counters are shown as controlled by the cutters 14 and 16, but this is not essential. The cutters are chosen for convenience, because each revolution of the cutter corresponds to the feeding and stacking of one sheet or any desired number of sheets (corresponding to the number of rolls 2) in the lay-boy 4. The counters could as well be controlled in accordance with the operation of some other means for operating upon the sheets, which operation is a measure of the number of sheets delivered in the lay-boy. It is preferable to employ some

operating mechanism of the machine for this purpose, because this renders it unnecessary to complicate the machine by the addition of extra mechanisms. All that is necessary is to connect the old operating mechanism, which is rendered especially easy if it comprises a rotating roll, to the counter and, through the counter, to the tag-inserting means, or marker. Nor is the invention restricted to the use of two counters only. A plurality of counters may be employed, selectively adapted, in conjunction with the markers, to mark or indicate sheets of the stack that are selectively predetermined by the respective counters.

It will be understood that the invention is not limited to the exact embodiment that is herein illustrated and described, and is subject to modification and change by persons skilled in the art. All such modifications and changes are considered to be within the spirit of the invention, and the scope of the invention is defined by the appended claims.

What is claimed as new is:

1. A machine of the class described having, in combination, a lay-boy, means for feeding sheets into the lay-boy, means for inserting the end of a strip between predetermined sheets of the stack from a position just to the rear and just below the upper sheets of the stack, and a cutter located between the lay-boy and the inserting means for severing the end of the strip.

2. A machine of the class described having, in combination, means for operating upon sheets of material that are adapted to be stacked, a lay-boy, means for stacking the sheets in the lay-boy, a feed roll for inserting the end of a strip between adjacent sheets of the stack, means controlled in accordance with the operation of the operating means to operate the feed roll through a portion of a revolution to insert the end of the strip between predetermined sheets of the stack, a cutter located between the lay-boy and the feed roll for severing the end of the strip, and means controlled in accordance with the operation of the operating means to operate the feed roll through another portion of a revolution to effect the operation of the cutter.

3. A machine of the class described having, in combination, means for stacking sheet material, and a feed roll situated just to the rear of the stack and just below the level of the stack and constructed and arranged to insert a tag between predetermined sheets of the stack.

4. A machine of the class described having, in combination, means for stacking sheet material, a counter operable in one direction of operation throughout to count the number of sheets stacked, means for inserting the end of a strip between adjacent

- sheets of the stack, means for severing the end of the strip, and a lever controlled by the counter in one position of its operation to cause the inserting means to insert the 5 end of the strip between adjacent sheets predetermined by the counter and controlled by the counter in another position of its operation to effect the operation of the severing means.
- 10 5. A machine of the class described having, in combination, means for stacking sheet material, a counter having a counting disk rotatable in one direction only to count the number of sheets stacked, means for inserting the end of a strip between adjacent 15 sheets of the stack, means for severing the end of the strip, a lever adapted to occupy two positions successively in one of which it controls the operation of the inserting means and in the other of which it controls the operation of the severing means, and a cam rotatable with the counting disk having two portions adapted respectively to control the lever in the two positions.
- 20 6. A machine of the class described having, in combination, means for stacking sheet material, means for inserting a tag between adjacent sheets of the stack, and a plurality of means for selectively controlling the inserting means to cause the inserting means to insert the tag between sheets 30 of the stack selectively predetermined by the respective controlling means.
- 35 7. A machine of the class described having, in combination, means for stacking sheet material, a feed roll for inserting a tag between adjacent sheets of the stack, and two means selectively adapted to actuate the feed roll to cause the feed roll to 40 insert the tag between sheets of the stack selectively predetermined by the respective feed-roll-actuating means.
- 45 8. A machine of the class described having, in combination, means for stacking sheet material, a feed roll for inserting a tag between adjacent sheets of the stack, a roll connected to the feed roll so that the rotation of either roll effects the rotation of the other roll, and means for actuating 50 either roll.
- 55 9. A machine as described in claim 8 in which the rolls are separated from their connecting means by a partition.
- 60 10. A machine of the class described having, in combination, means for stacking sheet material, a plurality of counters for counting the number of sheets stacked, and means for inserting a tag between adjacent sheets of the stack, the counters being adapted to control the inserting means selectively to cause the inserting means to insert the tag between sheets of the stack selectively predetermined by the respective counters.
- 65 11. A machine of the class described having, in combination, two shafts, a roll loosely mounted on each shaft, means connecting the rolls to cause the rotation of either roll to effect the rotation of the other roll, means for securing either roll to the shaft upon which it is mounted, and means for selectively rotating the shafts.
- 70 12. A machine of the class described having, in combination, means for stacking sheet material, two counters for counting the number of sheets stacked, two rotatable shafts, a roll loosely mounted on each shaft, one of the rolls being adapted to insert a tag between adjacent sheets of the stack, means connecting the rolls to cause the rotation of either roll to effect the rotation of 75 the other roll, and means for securing either roll to the shaft upon which it is mounted, the rotation of the shafts being selectively controlled by the counters to cause the tag-inserting roll to insert the tag between 80 sheets of the stack selectively predetermined by the counters.
- 85 13. A machine of the class described having, in combination, means for stacking sheet material, a feed roll for inserting the end of 90 a strip between predetermined sheets of the stack, means for severing the end of the strip, a roll having means for controlling the severing means connected to the feed roll so that the rotation of either roll effects the 95 rotation of the other roll, and means for actuating either roll.
- 100 14. A machine of the class described having, in combination, a lay-boy, means for stacking sheet material in the lay-boy, means 100 rotatable through a portion of a revolution to insert the end of a strip between adjacent sheets of the stack, and rotatable through another portion of a revolution to sever the end of the strip, and means for 105 first rotating the rotatable means through the first named portion of a revolution, then maintaining the rotatable means temporarily stationary, and finally rotating the rotatable means through the other portion of the revolution.
- 110 15. A counter having, in combination, a counting tooth-controlled disk, a pawl movable in one direction only along a circumference to engage the controlling teeth of 115 the counting disk to actuate the counting disk, and means whereby the pawl is adapted to actuate the counting disk to a degree corresponding to a predetermined number of the controlling teeth of the counting disk 120 upon each movement of the pawl throughout the circumference.
- 125 16. A counter having, in combination, a counting disk having a gear, a gear meshing with the counting-disk gear, a ratchet movable with the meshing gear, a pawl for engaging the teeth of the ratchet, whereby actuation of the pawl effects the actuation of the counting disk, a track located along a 130 portion of the periphery of the ratchet, and

means for actuating the pawl along the periphery of the ratchet, the pawl being adapted to run idly along the track during its actuation over the said portion of the periphery of the ratchet, whereby the pawl is adapted to actuate the ratchet through an angle corresponding to the remaining portion of the periphery of the ratchet upon each actuation of the pawl.

- 10 17. A counter having, in combination, a rotatable ratchet wheel, a counting disk controlled by the ratchet wheel in accordance with the degree of rotation of the ratchet wheel, a rotating pawl adapted to engage the 15 teeth of the ratchet wheel to rotate the ratchet wheel, and a plurality of segmental members having cam tracks over which the pawl is adapted to ride idly, the segmental members being adjustable to expose a variable 20 number of the teeth of the ratchet wheel, whereby the pawl is adapted to actuate the ratchet wheel through an arc corresponding to the number of teeth exposed upon each rotation of the pawl.
- 25 18. A counter having, in combination, a shaft adapted to be continuously rotated, an arm extending from and rotating with the shaft, a pawl mounted at the end of the arm, a ratchet wheel loosely mounted on the shaft 30 the teeth of which are adapted to be engaged by the pawl, whereby the ratchet wheel is adapted to be rotated about the shaft by the pawl, a plurality of segmental members having cam tracks over which the pawl is adapted 35 to ride idly, the segmental members being adjustable to expose a variable number of teeth of the ratchet wheel, whereby the pawl is adapted to actuate the ratchet wheel through an arc corresponding to the number 40 of teeth exposed upon each rotation of the pawl, a pinion secured to the ratchet wheel so as to rotate therewith, a counting disk having gear teeth meshing with the teeth of the pinion, and an indicator for the 45 counting disk.

19. A machine of the class described having, in combination, a lay-boy, means for stacking sheets in the lay-boy, a feed roll for inserting the end of a strip between adjacent sheets of the stack, means for severing the end of the strip, means rotatable through a portion of a revolution to operate the feed roll to insert the end of the strip between adjacent sheets of the stack, and rotatable 50 through another portion of a revolution to sever the end of the strip, and means for first rotating the rotatable means through the first-named portion of a revolution, then maintaining the rotatable means temporarily 55 stationary, and finally rotating the rotatable means through the other portion of the revolution.

20. A machine of the class described having, in combination, means for stacking sheet material a counter for counting the number

of sheets stacked, means for inserting the end of a strip between adjacent sheets of the stack, means for severing the end of the strip, and a lever controlled by the counter in one position of its operation to cause the 70 inserting means to insert the end of the strip between adjacent sheets predetermined by the counter and controlled by the counter in another position of its operation to effect the operation of the severing means. 75

21. A machine of the class described having, in combination, means for stacking sheet material, a counter for counting the number of sheets stacked, means for inserting the end of a strip between adjacent sheets of the 80 stack, means for severing the end of the strip, and a lever adapted to occupy two positions successively in one of which it controls the operation of the inserting means and in the other of which it controls the operation of the severing means, the counter having a cam having two portions adapted respectively to control the lever in the two positions.

22. A machine of the class described having, in combination, a normally stationary member provided with a recess, a pawl movable in a predetermined path adapted to engage the walls of the recess to effect the actuation of the member, a gate in the path of the pawl normally covering the recess, and means for actuating the gate to uncover the recess, the pawl thereupon engaging the walls of the recess to actuate the member until the recess is again covered by the gate, the actuating means being adapted to actuate the gate to again uncover the recess, and the pawl being adapted to thereupon again engage the walls of the recess to actuate the member until the recess is once more covered 105 by the gate.

23. A machine of the class described having, in combination, means for stacking sheet material, a shaft having a recess, a feed roll mounted upon the shaft for inserting a tag 110 between adjacent sheets of the stack, a pawl movable around the shaft adapted to engage the walls of the recess to rotate the shaft and the feed roll mounted on the shaft, a gate in the path of the pawl normally covering the recess, and means for actuating the gate to uncover the recess. 115

24. A machine of the class described having, in combination, means for stacking sheet material, a shaft having a recess, a feed roll mounted upon the shaft for inserting the end of a strip between adjacent sheets of the stack, means operable at a predetermined point in the rotation of the shaft for severing the strip, a pawl movable around the shaft adapted to engage the walls of the recess to rotate the shaft and the feed roll mounted on the shaft, a gate in the path of the pawl normally covering the recess, and means for actuating the gate to uncover the 120 125 strip.

- recess, the pawl thereupon engaging the walls of the recess to rotate the shaft until the recess is again covered by the gate, whereby the feed roll inserts the end of the strip 5 between adjacent sheets of the stack, the actuating means being adapted to return the gate to its normal position, thereby again uncovering the recess, and the pawl being adapted to thereupon again engage the walls 10 of the recess to return the shaft to its normal position, effecting the actuation of the severing means.
25. A method of feeding and stacking sheet material that comprises feeding and 15 stacking the sheets, feeding the end of a strip at an upward incline over the rear of the stack to cause the next-following sheet stacked to engage the said end of the strip and lay it flat against the next-preceding
- sheet, continuing to feed and stack the 20 sheets, and severing the said end of the strip upon the addition of a predetermined number of sheets to the stack.
26. A machine of the class described having, in combination, means for stacking 25 sheet material, means for feeding the end of a strip at an upward incline over the rear of the stack, whereby the next-following sheet stacked will engage the said end of the strip and lay it flat against the next-preceding 30 sheet, and means for severing the said end of the strip upon the addition of a predetermined number of sheets to the stack.
- In testimony whereof, I have hereunto subscribed my name this 19th day of May, 35 1922.

CHARLES B. MAXSON.

- recess, the pawl thereupon engaging the walls of the recess to rotate the shaft until the recess is again covered by the gate, whereby the feed roll inserts the end of the strip 5 between adjacent sheets of the stack, the actuating means being adapted to return the gate to its normal position, thereby again uncovering the recess, and the pawl being adapted to thereupon again engage the walls 10 of the recess to return the shaft to its normal position, effecting the actuation of the severing means.
25. A method of feeding and stacking sheet material that comprises feeding and stacking the sheets, feeding the end of a strip at an upward incline over the rear of the stack to cause the next-following sheet stacked to engage the said end of the strip and lay it flat against the next-preceding 30 sheet, and means for severing the said end of the strip upon the addition of a predetermined number of sheets to the stack.
26. A machine of the class described having, in combination, means for stacking sheet material, means for feeding the end of a strip at an upward incline over the rear of the stack, whereby the next-following sheet stacked will engage the said end of the strip and lay it flat against the next-preceding 35 sheet, and means for severing the said end of the strip upon the addition of a predetermined number of sheets to the stack.

In testimony whereof, I have hereunto subscribed my name this 19th day of May, 1922.

CHARLES B. MAXSON.

CERTIFICATE OF CORRECTION.

Patent No. 1,611,476, granted December 21, 1926.

to CHARLES B. MAXSON.

It is hereby certified that error appears in the printed specification of the above mentioned patent requiring correction as follows: Page 3, lines 71 to 74, strike out "It is therefore preferred to feed the strip as illustrated and described in a copending application, Serial No. 664,775, filed September 25, 1923.", and insert the same to follow after the period and word "reams", line 79; same page line 113, for the numeral "9a" read "10a"; page 6, line 56, for the word "disks" read "disk"; page 9, line 65, claim 20, after the word "material" insert a comma; and that the said Letters Patent should be read with these corrections therein that the same may conform to the record of the case in the Patent Office.

Signed and sealed this 22nd day of February, A. D. 1927.

Seal.

M. J. Moore,
Acting Commissioner of Patents.
